United States Patent Office.

GARRET C. LANSING AND JOHN G. OSTROM, OF RHINEBECK, NEW YORK.

Letters Patent No. 65,681, dated June 11, 1867.

IMPROVEMENT IN WAGON-SPRINGS.

The Schedule referred to in these Letters Patent and making part of the same.

TO ALL WHOM IT MAY CONCERN:

Be it known that we, JOHN G. OSBORN and GARRET C. LANSING, of Rhinebeck, Dutchess county, New York, have invented an improved Wagon-Spring; and we do hereby declare that the following is a full, clear, and exact description thereof, which will enable others skilled in the art to make and use the same, reference being had to the accompanying drawings, forming part of this specification.

The object of this invention is to provide a very simple and cheap but a very elastic spring, or rather set of springs, for wagons and sleighs; and the invention consists in arranging a series of pairs of flat wooden springs, each pair being laid at right angles across the pair above, so that the more sets of springs are applied the greater will be the elasticity of the whole. In the annexed drawings our invention is illustrated—

Figure 1 being a side view of a wagon-box provided with our improved springs.

Figure 2 is a bottom view of the same.

Similar letters of reference indicate corresponding parts.

A is a wagon-box, made as usual, and of any suitable material. Across its bottom, and near to the ends of the same, are secured two flat wooden springs, a , a , by means of plugs b , b , or otherwise, whereby a space is left between a and A, and thus as the plugs are arranged at or near to the ends of the springs the elasticity of the latter is not destroyed, the centre of the springs not coming in contact with the wagon-body or any projection thereon. Near to the ends of the springs a , a are secured, by means of screws or otherwise, and at right angles with the former, springs a' , a' . Across these are arranged springs a'' , a'' , the same being nearer to the centre of the wagon than the springs a , a ; and at right angles with a'' , a'' , are arranged springs a''' , a''' , which are or may be further apart than a' , a' , and so forth, each pair being arranged at right angles across the pair above, until a sufficient number of such pairs are arranged to insure the required elasticity. The lowest pair is then secured to the front and rear axles of a wagon, or to the runners of a sleigh, in any suitable manner.

We do not claim any particular number of such pairs of springs, four being the lowest employed; nor do we claim the manner of securing the springs to each other, or to the runners or axle or to the box. If desired the perch can be omitted when these springs are used, but when required it may be used as usual.

We claim as new, and desire to secure by Letters Patent—

The flat wooden springs a , a' , a'' , a''' , etc., when arranged in pairs, each pair at right angles across the other, substantially as and for the purpose herein shown and described.

GARRET C. LANSING,
JOHN G. OSTROM.
